TRANSFUSION EQUIPMENT

William C. Wootton, Centerville, Calif., assignor, by
mesne assignments, to United-Carr Fastener Corpora-
tion, Boston, Mass., a corporation of Delaware

Application April 16, 1954, Serial No. 423,661

4 Claims. (Cl. 128—214)

This invention relates generally to an assembly useful
in making blood transfusions.

The object of the invention is to provide a combination
tubing clamp and needle assembly which is adapted for
economical manufacture so that it may be thrown away
after one use.

A further object of the invention is to provide an as-
sembly for use on a transfusion flask which provides means
for both retaining the hypodermic needle and controlling
the flow of blood therethrough.

Other objects will, in part, be obvious, and will, in part,
appear hereinafter.

In the drawing:

Fig. 1 is a view in side elevation of a tubing clamp and
needle assembly embodying the features of the invention;

Fig. 2 is a top plan view of the assembly of Fig. 1;

Fig. 3 is a bottom plan view of the assembly of Fig. 1;

Fig. 4 is a view in section taken on line 4—4 of Fig. 1;

Fig. 5 is a view of the assembly of Fig. 1 with the tubing
in the closed position; and

Fig. 6 is a top plan view partly in section of the as-
sembly of Fig. 5.

Referring to the drawing, there is illustrated a combina-
tion tubing clamp and needle assembly 10, which is adapt-
ed for use as a hand-grip device to be inserted through the
stopper of a transfusion flask to control the flow of blood
into the flask.

The assembly 10 comprises generally upper and lower
colateral members 12 and 14 which are secured together
at their end portions 16 and 18.

The members 12 and 14 have superimposed portions
20 and 22 adjacent the end 16, and spaced apart portions
24 and 26 adjacent the end 18. The superimposed portions
20 and 22 are provided with longitudinal embossed
channels 28 and 30, and the portion 24 of the upper mem-
ber, which is arched upwardly away from the portion 26
of the lower members is provided with a longitudinally
extending tapered opening 32.

A needle 34, having a tubing 36 assembled onto an end
thereof, is disposed between the superimposed portions
20 and 22 in the channels 28 and 30 so that the end portion
surrounded by the tubing is firmly gripped by the
portions 20 and 22 to retain the needle and tubing in as-
sembly. A series of transverse embossments 37 may be
provided in the channels to assist in preventing longitudi-
nal movement of the needle therein.

The tubing 36 protrudes from between the superimposed
portions about the projecting portion of the needle a suffi-

2

cient distance to enable a sterile cap 38 to be assembled
therein to protect the needle. The tubing 36 also extends
from between the superimposed portions into the space be-
tween the portions 24 and 26 and then through the tapered
aperture 32, so that the flow of fluid through the tubing
may be controlled by movement of the tubing in the aper-
ture to restrict or completely close the tubing.

The assembly illustrated and described herein is par-
ticularly suited for rapid and economical manufacture, so
that it may be thrown away after a single use, thereby
eliminating problems of sterilizing the apparatus for re-
use.

Since certain obvious modifications may be made in
the device without departing from the scope of the inven-
tion, it is intended that all matter contained herein be
interpreted in an illustrative and not in a limiting sense.

I claim:

1. A combination tubing clamp and needle holder, com-
prising a pair of colateral members having superimposed
portions at one end, one of said members having a por-
tion at the other end which is arched upwardly away
from the other member, said superimposed portions hav-
ing means for gripping a hypodermic needle, said up-
wardly arched portion having a tapered opening for
receiving a tubing leading to the hypodermic needle.

2. A combination tubing clamp and hypodermic needle
holder, comprising a pair of colateral members having
superimposed portions at one end and spaced portions at
the other end, cooperating longitudinal embossments in
said superimposed portions to receive and grip a hypo-
dermic needle and a tapered opening in one of said mem-
bers in the spaced portion to receive a tubing therethrough.

3. A tubing clamp and hypodermic needle assembly,
comprising a pair of colateral members having super-
imposed portions at one end and spaced portions at the
other end, one of said members having a tapered opening
in the portion spaced from the other member, said mem-
bers having longitudinal embossments forming a channel
therebetween and a needle and tubing assembly assem-
bled with the members, said needle extending an appreciable
distance into the end portion of the tubing, and said end
portion being disposed in the channel and being gripped
by the colateral members with the needle protruding there-
from, said tubing extending through said tapered opening.

4. A tubing clamp and hypodermic needle assembly,
comprising a pair of colateral members having superim-
posed portions at one end and spaced portions at the
other end, one of said members having a tapered opening
in the portion spaced from the other member, said mem-
bers having longitudinal embossments forming a channel
therebetween, and a needle and tubing assembly assem-
bled with the members, said needle extending an appreciable
distance into the end portion of the tubing, and said end
portion being disposed in the channel and being gripped
by the colateral members, said needle protruding from
between said members, at one end of the superimposed
portions, said tubing protruding from the other end of
the superimposed portion into the space between said
spaced portions and extending through said tapered slot.
